UNITED STATES PATENT OFFICE.

WALTON DUANE SMITH, OF PROPHETSTOWN, ILLINOIS, ASSIGNOR OF TWO-THIRDS TO FRED. L. ADAMS AND A. D. ADAMS, OF SAME PLACE.

SAMPLE-HOLDER.

SPECIFICATION forming part of Letters Patent No. 549,940, dated November 19, 1895.

Application filed May 11, 1895. Serial No. 549,004. (No model.)

To all whom it may concern:

Be it known that I, WALTON DUANE SMITH, a citizen of the United States, residing at Prophetstown, in the county of Whiteside 5 and State of Illinois, have invented a new and useful Sample-Holder, of which the following is a specification.

This invention relates to an improvement in sample-holders.

10 The object of the present invention is to provide a new and useful sample-holder such as is employed for fastening or temporarily attaching samples to boxes, drawers, or the like which contain or hold duplicates of the 15 sample exhibited; and in the accomplishment of this object the invention contemplates a device that shall not only be simple and inexpensive, but at the same time capable of securely and removably holding in position 20 on the exterior of a box or the like samples of small wares, such as articles of hardware, harness, furniture-fixtures, &c.

With these and other objects in view, which will readily appear as the nature of the 25 invention is better understood, the same consists in the novel construction, combination, and arrangement of parts hereinafter more fully described, illustrated, and claimed.

In the drawings, Figure 1 is an end view of 30 a box, showing the herein-described sample-holder affixed thereto and holding in position an article of hardware. Fig. 2 is an elevation of the obverse side of a sample-holder constructed in accordance with this invention. Fig. 3 is a similar view of the reverse 35 or gummed side of the holder. Fig. 4 is a detail sectional view on the line 4-4 of Fig. 1. Fig. 5 is an elevation of a double form of the holder such as is employed for attaching long 40 or heavy samples to the outside of a box or the like.

Referring to the accompanying drawings, the numeral 1 designates a flexible adhesive 45 paster that is made of any suitable flexible material and is cut in any desired shape or form. The said flexible paster 1 is provided with a plain attaching side 2, that is flat throughout its entire area and is coated with gum or other suitable adhesive material 50 which when dampened will adhere to any

object to which the paster may be attached and when dried provides means for securely fastening the paster-body at all of its edges on the exterior of the box or other receptacle that contains goods or wares, a sample of 55 which is ordinarily exhibited on the outside of said box or receptacle.

The flexible paster 1 is preferably strengthened at a central point by a reinforcing piece 3, that is usually made of the same material 60 as the paster-body and is gummed or otherwise suitably secured to the ungummed side of the paster-body. The reinforcing piece 3 strengthens the paster-body at the point where the metallic fastening-clip 4 is arranged. The metallic fastening-clip 4 consists of a short narrow plate of sheet metal placed flat against the reinforcing piece 3 and provided at its extremities with the securing tongues 5, that are passed through the 65 reinforcing piece and the paster-body and are bent flat against the plain attaching side 2 of the paster-body to provide for permanently securing the fastening-clip to the ungummed side of the paster-body. 70

75 The metallic fastening-clip 4, that is secured to the ungummed side of the paster-body, provides means for fastening in position the flexible tie 6, which may be of a suitable length of tape, cord, or wire. The flexible tie 6 passes between the clip 4 and the paster-body and is securely held by said fastening-clip at an intermediate point, thereby leaving both ends of the tie free to be tied over the sample to be exhibited. After the 80 85 flexible paster-body has been gummed to a box or the like, as already described, it is simply necessary to tie the free ends of said tie around the ware or article to provide for firmly and securely holding such ware or article in position, while at the same time allowing the ware or article to be easily removed and replaced, as will be readily understood.

90 As described, the flexible paster-body may be made of any suitable flexible material and may be cut in any desired shape or form, thereby being susceptible to such modifications as illustrated in Fig. 5 of the drawings. In this figure of the drawings the paster-body is illustrated as being of an elongated 95 100

shape and provided with a double set of tie-strings located, respectively, near the ends thereof, and thereby providing a construction of sample-holder especially adapted for 5 use in attaching long or heavy samples.

Other changes in the form, proportion, and the minor details of construction may be resorted to without departing from the principle or sacrificing any of the advantages of 10 this invention.

Having thus described the invention, what is claimed, and desired to be secured by Letters Patent, is—

1. A sample holder consisting of a flexible 15 paster, the body of which is provided with a plain attaching side flat throughout its entire area and having thereon an adhesive coating, and a short metal plate arranged on the ungummed side of the paster body and having 20 its ends secured therein, said metal plate embracing the flexible tie at an intermediate point between its ends thereby leaving both

ends of the tie free to be tied around an object, substantially as set forth.

2. A sample holder consisting of a flexible 25 paster, the body of which is provided with a plain attaching side, flat throughout its entire area and having thereon an adhesive coating, a flexible tie, and a narrow metallic fastening 30 clip plate arranged flat against the ungummed side of the paster body over the flexible tie at a point intermediate of its ends, said clip being provided at its extremities with securing tongues passed through the paster body and bent flat against the plain attaching side 35 thereof, substantially as set forth.

In testimony that I claim the foregoing as my own I have hereto affixed my signature in the presence of two witnesses.

WALTON DUANE SMITH.
